Barracks, and Chester L. Eppley, Mount Holly
Springs, Pa.

Application May 9, 1944, Serial No. 534,736

7 Claims. (Cl. 126—45)

(Granted under the act of March 3, 1883, as
amended April 30, 1928; 370 O. G. 757.)

1

The invention described herein, if patented, may be manufactured and used by or for the Government for governmental purposes, without the payment to us of any royalty thereon.

This invention relates to an improved portable gasoline stove of the single burner type designed for use especially by individual soldiers and small groups of men in field operations of the Army.

It is an object of this invention to provide a pressureless gasoline stove having as simple a construction as possible and having no parts which require replacement even after extended periods of use.

It is the further object of this invention to provide a stove capable of burning out completely a single charge of gasoline for the purpose of heating food or other materials placed on top of the stove which is provided with a supporting rack for the purpose.

Other objects of the invention will appear from a consideration of the specification and the accompanying drawings in which:

Figure 1 is a perspective view of the assembled stove.

Figure 2 is a perspective view of the burner cap and a portion of the inside cylinder of the stove body, and

Figure 3 is a vertical sectional view through the center of the stove.

The stove consists of a body A having an annular reservoir or chamber 10 formed by an outside vertical wall 11 and an inner shorter wall 12 which forms a cylinder 13 open at both the top and bottom, the two walls being connected by a flat bottom-forming member 14. A base 15 is secured to the bottom 14 of the reservoir by means of the flange 16 and has a series of air admitting openings 17 in its vertical wall 18. The open top of the outer wall 11 provides a support for a combined grate and former B for the flame, while the inner wall 12 supports an air-controlling burner cap and flame directing member C.

The grate B is removable from the stove body A and comprises an upwardly opening channel member 21 of annular form, having a flat bottom 22 and two upstanding walls 23 and 24 approximately the same height. The outer wall 23 has a turned-out flange 25 at its upper edge which is adapted to rest on the outer body wall 11 and support the grate, the channel member 21 being telescoped within the outer body wall 11. Grate bars 26, e. g. five in number, are supported on the outer wall 23 and flange 25 of the grate and extend radially toward the center to ap-

proximately the inner wall 24. The upper outside corners 27 of the grate bars are rounded and the inner corners 28 are cut back at an angle to the top. A ring support 29 is provided for the grate bars 26 between the inner and outer walls of the channel member. The ring is supported by legs 30 resting on and secured to the annular bottom 22 of the grate, and the grate bars 26 are rigidly secured to it. The inner wall 24 of the channel member 21 is provided with a series of apertures 31.

The burner cap C is inserted in the top of the inside cylinder 13 of the reservoir to form means for admitting air to the flame and for confining the flame as it emerges from the stove. The burner cap C consists of a circular plate 32 flanged downwardly at its outer rim and then inwardly for a short distance and then downwardly again, forming flanges 33, 34 and 35. The flange 35 is inserted telescopically into the inner cylinder 13, the inwardly extending flange 34 resting on top of the cylinder. The plate 32 has a row of perforations 36 around it near its periphery and the vertical flange 33 also has a row of apertures 37 at the level of the top of the collar 38, which is secured within the downwardly extending flange 35 and extends both above and below the edges of the flange 35 of the burner cap. Centrally of the plate 32 there is secured a finely perforated brass cylinder 39 which, when the burner cap is in position, extends upwardly through the center of the channel member 21 of the grate to a point somewhat below the top of the inner flange 24, the walls of the two members being spaced to form a flame passage. Air enters the cylinder through the open top and passes through the perforations to mingle with the mixture of fuel vapor and air being burned between the cylinder 39 and the flange 24.

40 The annular reservoir 10 of the stove body A is provided with a molded asbestos wick 40 which substantially fills the chamber below the projecting portion formed by the flanges 33 and 34 of the burner cap, and which is preferably slightly concave on the top as at 41. The wick 40 provides a porous reservoir for the gasoline which also regulates the consumption of the gasoline supply. If the wick is not provided or is not available when it is desired to use the stove, it 45 may be replaced by substantially the same volume of sand or porous earth.

Around the body A of the stove is placed a cylindrical shield or wind screen 42 frictionally secured to the body of the stove by a plurality of (e. g. four) springs 43 which are equally spaced

around the shield and spot welded or otherwise secured as by rivets 44 to the inner surface. These springs 43 project below the shield to form feet 45 to space the shield from a supporting surface, such as the ground, so that air can reach the openings 17 in the base for the stove. Shield 42 extends across the plane of perforations 37 for better control of the vapor passage through the latter. The air space 46 between the shield 42 and the stove body A serves to equalize and regulate the heating of the reservoir containing the wick and gasoline, thereby promoting and controlling the vaporization of the gasoline and making the stove burn more steadily, especially when used in a drafty or windy location. Since 15 vaporization of the fuel depends on the heat transmitted thereto from the burner, it is important that the reservoir be insulated so that vaporization of all the fuel may take place evenly.

A carrying handle 47 may be provided for the entire unit which should preferably be secured to the outside wall of the body A by means of ears 48.

A preferred embodiment of the invention consists of a stove body A substantially six inches in diameter and $4\frac{1}{2}$ inches high. The inner cylinder 13 should be approximately $2\frac{1}{2}$ inches in diameter and three inches high and the base 15 should be approximately $1\frac{1}{2}$ inches high. The base perforations 17 should be approximately $\frac{1}{2}$ inch in diameter and spaced $\frac{1}{2}$ inch from the bottom edge of the base and may be twelve in number. The inner opening of the grate B should be $2\frac{3}{4}$ inches in diameter and the central cylinder 39 of the cap C should be approximately $2\frac{3}{8}$ inches in diameter and $\frac{1}{2}$ inch high, leaving a flame opening 49 about $\frac{3}{8}$ inch wide between the two members B and C.

The apertures 31 in the inner flange 24 of the grate are spaced approximately midway between the top and bottom of the flange. In order to secure a properly balanced supply of air and fuel vapor for the burner there may be provided twenty-two $\frac{3}{32}$ inch apertures 31, fifty-three $\frac{1}{16}$ apertures 36 in the plate 32 and fifty-three $\frac{1}{16}$ apertures 37 in the flange 33.

In operation the grate B is lifted from the body of the stove and three to four ounces of gasoline are evenly distributed over the asbestos or sand. The grate is replaced and the stove is lighted by applying a flame to the annular opening 49 above the burner formed between the grate B and the burner cap C. Air enters the stove through the perforations 17 in the base and flows upwardly through the small inner cylinder 13 of the body. Inside the burner cap C the air mixes with the vaporized fuel entering through the openings 37 and this mixture escaping through the openings 36 is ignited at the outside of the cap. Additional fuel vapor from the annular opening between the burner cap and the grate is entrained in the current flowing upwardly through the openings 36, and additional air for completing the combustion of the fuel vapor enters the flame passage through the openings 31 in the grate and through the perforated cylinder 39. The flow of fuel vapor through the cap is promoted by the fact that the collar 38 extends upwardly to the level of the apertures 37 and thus acts as a baffle. This directs the air rising through the center of the reservoir upwardly through the openings 36 and tends to draw fuel vapor in through the openings 37. The rate of fuel consumption is about three ounces of gasoline per hour. Canned food, utensils or

whatever it is desired to heat may be supported on the grate B.

This construction provides a stove which is adapted for camping and other outdoor or temporary use as well as for military purposes. It provides for safe, simple and efficient operation and there are no working parts to become clogged, broken, lost, or out of adjustment. At the same time it furnishes a regulated supply of heat with maximum fuel utilization and efficiency in combustion because of the relation between the grate and the burner cap and the design of the air admitting apertures.

The invention accordingly consists in the features and arrangements exemplified in the structure heretofore described, the scope and application of which are indicated in the following claims.

We claim:

1. A pressureless gasoline stove comprising an annular fuel reservoir having spaced outer and inner walls and adapted to receive fuel absorbent material, said reservoir having its outer wall higher than its inner wall, a removable grate and flame restricting member mounted on said outer wall and extending inwardly toward said inner wall to cover the reservoir and form a restricted passage with said inner wall, and a removable burner cap supported on said inner wall in spaced relation to said grate and receiving air from below to the space within the inner wall, said cap having perforations for the admission of fuel vapor and perforations for the escape of mixed vapor and air, said last-named perforations being located in a plane above said first-named perforations.

2. A pressureless gasoline stove comprising an annular fuel chamber having an inner wall forming a central air-admitting passage and an outer wall spaced from said inner wall, said inner wall having at its top a perforated extension, and a removable grate supported on said outer wall and extending inwardly to cover said fuel-chamber and forming a restricted passage with said inner wall and said perforated extension, said grate comprising an upwardly opening annular channel member and a series of grate bars supported across said annular channel on the outer and inner rims of said channel, whereby said annular channel and said grate bars may be unitarily removed from or inserted into said stove.

3. A pressureless gasoline stove comprising an annular absorbent filled fuel reservoir, a central air admitting passage being provided within said reservoir, means forming a burner space at the end of said passage and communicating with said passage and with said reservoir, said fuel being vaporizable in the reservoir by the heat of combustion in said space, said last-named means having perforations for the admission of fuel vapor and perforations for the escape of mixed vapor and air, said last-named perforations being located in a plane above said first-named perforations, an apertured base for said reservoir through which air is supplied to said central passage, and a wind screen having means frictionally securing it to said stove body and forming an insulating chamber around said reservoir, said wind screen extending upwardly across the plane of said first-named perforations in said burner cap, and said wind screen securing means projecting below said wind screen to support it in spaced relation to the bottom edge of said apertured base.

4. A portable gasoline stove comprising an an-

nular open-topped fuel chamber having an inner cylindrical wall forming a central air passage and a higher outer wall, a removable grate having a channel-shaped annulus telescoped within said fuel chamber and grate bars extended transversely across said annulus, said annulus having an external flange resting on the top of said outer wall, and a removable burner cap having a portion telescoped within said lower inner cylindrical wall and a flat-topped portion projecting above said wall, said last mentioned portion having series of perforations on its side and around its top and an upwardly projecting perforated cylinder secured to said top and extending within and spaced from said annulus to form a flame passage.

5. A portable gasoline stove comprising an annular fuel reservoir having a central air admitting passage, a burner cap mounted over said central passage, means providing an annular burner passage adjacent said cap, said cap having a portion enlarged to extend over the reservoir and having a perforated zone at the side to draw in fuel vapor from the reservoir and having perforations in a plane above said zone for the escape of mixed air and vapor, and means within said cap to direct the incoming air toward said last-named perforations.

6. A stove as defined in claim 5, wherein said first-named means comprise a cylindrical extension on said cap and an annular grate carried by said reservoir, said grate and said burner cap extension being perforated for the admission of air to the flame.

7. A portable gasoline stove comprising an an-

10 nular fuel reservoir having a center air-admitting passage, a burner cap mounted over said center passage, means providing an annular burner passage adjacent said cap, said cap having a portion enlarged to extend over the reservoir and having a perforated zone at the side to draw in fuel vapor from the reservoir and having perforations in a plane above said zone for the escape of mixed air and vapor, and annular baffle means within the cap to direct the incoming air towards said last-named perforations.
